FISHING LURE

Armand Mayer, Windsor, Vt.

Application December 20, 1954, Serial No. 33,603

Term of patent 14 years

(Cl. D31—4)

Fig. 1.

Fig. 3.

Fig. 2.

Fig. 4.

Fig. 1 is a side elevational view of a fishing lure embodying my new design;

Fig. 2 is a top plan view;

Fig. 3 is an end elevational view taken from the left of Fig. 1; and

Fig. 4 is another end elevational view thereof taken from the right of Fig. 1.

I claim:

The ornamental design for a fishing lure, as shown.
